UNITED STATES PATENT OFFICE

119,300

DESIGN FOR A LAVATORY UNIT

James E. Bales, Aurora, Ill., assignor to The Showerway Company, Minneapolis, Minn., a corporation of Minnesota

Application December 20, 1939, Serial No. 89,027

Term of patent 14 years

To all whom it may concern:

Be it known that I, James E. Bales, a citizen of the United States and residing in the city of Aurora, county of Kane, State of Illinois, have invented a new, original, and ornamental Design for a Lavatory Unit, of which the following is a specification, reference being had to the accompanying drawing, forming a part thereof, wherein,

Fig. 1 is a front perspective view of a lavatory unit showing my new design, and

Fig. 2 is a top plan view of the same.

I claim:

The ornamental design for a lavatory unit, as shown.

JAMES E. BALES.
